(57) **CLAIM**

The ornamental design for a cap for container as shown and described.

DESCRIPTION

FIG. 1 is a top perspective view of a cap for container showing our new design;

FIG. 2 is a bottom perspective view thereof;

FIG. 3 is a left side view thereof;

FIG. 4 is a right side view thereof;

FIG. 5 is a back view thereof;

FIG. 6 is a front view thereof;

FIG. 7 is a top view thereof; and,

FIG. 8 is a bottom view thereof.

The broken lines in the figures depict portions of the cap for container that form no part of the claimed design.
